To all whom it may concern:

Be it known that I, ALBERT BAUMGARTEN, a citizen of the United States of America, residing at Freeport, in the county of Stephenson and State of Illinois, have invented a new and original Design for Nut-Pick Holders, of which the following is a specification.

In the accompanying drawings, Figure 1 is a perspective view of a nut-pick holder embodying my novel design. Fig. 2 is a section at 2 2, Fig. 1.

As shown in the views, the nut-pick holder consists of a plain horseshoe-shaped body A, having a downturned flange A' around its outer margin and provided with calks and 15 along each branch with apertures a a' a'', central panels B, connecting the two branches and lying in their plane, and legs a³ a⁴ a⁵, projecting downward at the calk-points beyond the body and its flange. These are the 20 leading features of my design.

What I claim is—
